Patented Aug. 19, 1913.

UNITED STATES PATENT OFFICE.

LORA W. STOCKWELL, OF LOS ANGELES, CALIFORNIA.

WIRE-MATTRESS BED-BOTTOM.

1,070,928.

Specification of Letters Patent. Patented Aug. 19, 1913.

Application filed November 4, 1909. Serial No. 526,258.

To all whom it may concern:

Be it known that I, LORA W. STOCKWELL, a citizen of the United States, residing at Los Angeles, in the county of Los Angeles and State of California, have invented new and useful Improvements in Wire-Mattress Bed-Bottoms, of which the following is a specification.

This invention relates to a bed bottom in which a woven resilient wire mattress fabric is secured to a frame and drawn taut by resilient means a portion of which are diagonally arranged. The woven wire fabric referred to is made of spring coils spun together in a well-known manner commonly in vogue with woven wire mattresses.

An object of this invention is to provide a superior mattress of this kind which will be practical and efficient to hold the woven wire fabric well stretched throughout the portion thereof upon which the occupants of the bed normally rest, and yet preserve this soft and yielding nature of the woven wire fabric.

This invention is an improvement upon the wire mattress patented to C. S. Lloyd, Aug. 12, 1902, No. 706,970, and consists in various devices and features of invention whereby the stretching rail shown in said patent is dispensed with and a lighter, tighter and stronger bed bottom is provided. Provision is also made whereby sagging at the middle of the bed may be insured against and, if desired, the bed at the sides of the medial line of the bed may be more yielding than the bed at the medial line.

In devices of the kind heretofore known, the side pull or lateral tension is insufficient to properly support the wire fabric over the areas farthest removed from the supports and in attempting to overcome the difficulty the marginal areas of the fabric have been put under increased tension which, of course, modifies to an objectionable extent the resiliency of the marginal areas.

An object of this invention is to overcome the foregoing difficulty and this I do by providing the woven fabric at intervals from side to side with longitudinally extending wires, of which the medial one is straight from end to end and those on both sides of the medial line are deflected outward near their ends at angles of substantially thirty degrees away from the medial wire and all of which are provided with helical tension springs.

The accompanying drawings illustrate the invention.

Figure 1 is a plan showing the under side of a bed bottom constructed in accordance with this invention. Fig. 2 is an enlarged fragmental view of the top side of the bed bottom shown in Fig. 1. Only a portion of the wire fabric is shown. Fig. 3 is a fragmental sectional view from line x^3 , Figs. 1 and 2. Fig. 4 is a fragmental sectional view from line x^4 , Figs. 1 and 2. Fig. 5 is a fragmental sectional view from line x^5 , Figs. 1 and 2. Fig. 6 is a fragmental sectional detail of one of the end bars and clutch bar and anchor portion of the mattress frame just before the clutch bar is fastened in place.

The frame of the bed bottom may be of any desired construction and may be of any desired material.

In the form shown in the drawings 1 and 2 designate the side rails, 3 end-bars mounted in notches 4 at the ends of the side rails 1, 2, and provided with grooves 5 that extend centrally along their outer edges from end to end thereof. The woven resilient fabric a which is formed of relatively fine wire woven together in such manner as to make the fabric resilient, is stretched over the end-bars and its ends are crimped into the grooves 5 by the tongues 6 that extend centrally along the inner sides of the clutch-bars 7. The clutch-bars are fastened to the end-bars by suitable means as the nails or screws 8. The woven wire fabric is of common construction provided with longitudinal reinforcing spirals 9 which may be arranged at as frequent intervals as may be desired.

Extending lengthwise of the bed bottom and along the reinforcing spirals, are a series of relatively coarse bent wires each of which has a body 10 extending along inside of a coil practically from end to end of the suspended woven spring wire fabric and deflecting members 11, 12, practically at the extremities of the fabric body, that extend obliquely away from the medial line of the fabric and are provided at their extremities with coupling devices as the hooks or eyes 13. Anchor wires 14, each provided with an anchor portion 15, are gripped tightly between the end-bars 3 and the clutch-bars, 7, being crimped into the grooves 5 by the tongue 6. Said anchors are provided at their inner ends with coupling devices as

hooks or eyes 16 and extend obliquely from the end rails 3 toward the medial line of the fabric and practically in line with the deflecting members 11, 12, of the bent wires. Between the anchors and the deflecting members respectively are arranged helical springs 17 made out of relatively heavy spring wire and provided at their extremities with hooks or eyes 18 engaging the hooks or eyes 13 and 16 of the bent wires of their respective anchors. The anchor wires 14 and the coils of the fabric are both supported by the tops of the end bars 3; all resting on said tops and all are therefore held in practically a common horizontal plane, the practical deflection of the deflecting members and the anchors being laterally and not from the normal horizontal plane of the fabric. By extending the sliding bodies 10 from end to end of the fabric the portion of the fabric which supports the occupants of the bed is of practically uniform resilient construction throughout from end to end and from side to side, and the tension of the springs 17 is applied in such a manner as to afford comfortable and uniform support for the person.

To construct the device the anchors 14 are crimped into the grooves 5 in the cross bars 3 and are fastened by the staples 19; and the wire fabric α is applied over the anchors and crimped into the grooves 5 and may also be secured by staples if desired. The clutch bars 7 are then applied with their tongues 6 in the grooves 5 and thereupon the nails 8 or the fastening devices are driven home, thus jamming the tongues 6 on to the fabric and anchors to grip the same tightly without danger of splitting the end rails 3. Then the corners of the rails 3 may be set into the notches 4 and stretching mechanism, not shown, applied to draw the fabric taut. After or before this has been done the stretching wires 10 may be threaded into place through the spirals of the fabrics, preferably through the reinforcing spirals and the same are arranged so that the deflections 11, 12, of said wires will extend approximately in line with the anchors 14 but with a considerable space between the ends of the wires so that a helical or coil spring 17 may be interposed between each anchor and the end of the deflection. The helicals 17 at one end of the fabric may then be connected with the anchors and stretching wires as shown in the drawings and then the helicals at the other end will be separately connected with their stretching wires and by means of a stretching device, not shown, each helical may be stretched until its free end can be caught into the eye of the anchor.

As will be obvious by inspection of the figures the anchor wires 14 are of substan-

tial length and they are reasonably flexible. This feature is very important and has the following two-fold aspect.

As just explained above, the heavy springs 17 are first connected to the deflected ends 11 of the longitudinally extending wires 10, and the stretching or tensioning device not shown is gapped across the end rail 7 of the frame and across the adjacent end of the spring, for stretching the spring toward the anchor wire 14. While under the influence of this stretching device the hooks 18 of the springs could not be manipulated to any practical extent or with any degree of certainty so as to spring them into a rigid eye. By having wires 14, however, and by having them reasonably flexible the spring may be held firmly distended by the stretching device and the hooks or eyes 16 of the flexible anchor may be slipped over the distended spring. The stretching device is then of course removed and the springs forcibly draw up on the wires 10. The second useful aspect of the anchors 14 resides in the fact that they extend out a substantial distance from the end rail so that the springs are brought much closer to the point where the wires 10 start threading through the fabric. This reduces the length of the deflected ends 11. If the ends 11 were unnecessarily long, they would naturally be somewhat crooked especially in view of the fact that they were threaded through the fabric, and when the stretching device was released from the spring 17 some of the tension of the springs would exhaust itself in straightening out the crooked parts of ends 11. This would be unsatisfactory in that it would not throw the full spring tension on to the longitudinal portion of wires 10, as was anticipated, and the retensioning or reviving influence of spring 17 would be noticeably reduced from the expected amount. This effect is practically eliminated, however, by the construction shown, because the wires 14 can be made sufficiently straight for the purpose.

It is understood that while the drawings show the helicals provided with hooks at their ends to hook into the eyes on the ends of the wires and anchors, that a reverse construction may be employed, placing the hooks on the anchors and wires, to hook into the eyes on the helicals. It is thus seen that in constructing the bed bottom the wire fabric and the anchors may be fastened to the frame without applying lateral tension to the fabric, and that the spring coils may be connected to the anchors and the bent wires at one end of the bed bottom, and then the spring coils at the other end of the bed bottom may be separately brought into tension and caught into the ends of their respective anchors and stretching wires each coil being stretched separately so that the

power required to give a high tension to the wire fabric is independently applied to each of the coils and said coils can be placed under a high tension with the application of comparatively little power, and that the fabric on the frame is under tension lengthwise of the frame and that tension crosswise of the frame is effected by stretching lines the ends of which are deflected toward the edges of the fabric and are held under tension by detachable helicals that are independently stretchable and fastened to apply the requisite tension.

I claim:—

15 A rectangular bed bottom comprising a frame, a woven resilient fabric fastened to said frame, a continuous series of spaced longitudinally extending wires threaded

through said fabric for a portion of their length, both ends of each longitudinally extending wire being deflected toward the adjacent lateral side of the bed bottom, separate anchor wires of substantial length anchored to said frame and extending toward and substantially in line with said deflected ends of the corresponding longitudinally extending wires, and tension springs connected between the aforesaid deflected ends and the anchor wires.

In testimony whereof, I have hereunto set my hand at Los Angeles, California, this 29th day of October, 1909.

LORA W. STOCKWELL.
